UNITED STATES PATENT OFFICE.

CYRUS W. SALADEE, OF WASHINGTON, DISTRICT OF COLUMBIA.

ROAD-WAGON.

SPECIFICATION forming part of Letters Patent No. 228,397, dated June 1, 1880.

Application filed March 31, 1880. (No model.)

To all whom it may concern:

Be it known that I, CYRUS W. SALADEE, of Washington city, in the District of Columbia, have invented certain Improvements in Road-5 Wagons, of which the following is a specification embodying my said invention.

To enable others skilled in the art to make and use my invention, I herewith submit the following general description.

10 My invention relates to that class of road-wagons in which longitudinal semi-elliptic springs arranged upon different horizontal planes connect the axles as well as constitute the spring-platform; and my invention consists in connecting and combining the springs, as hereinafter described, and in the application of one or more spring-braces, so as to prevent side motion and secure greater flexibility.

20 In the drawings forming part of this specification, Figure 1 is a side elevation, in part section, of the running-gear of a road-wagon, showing my improvements; Fig. 2, a plan of the same; Figs. 3 and 4, views showing modifications; Fig. 5, a side view, showing a form of leaf-springs.

25 A A are the side springs, connecting, in the present instance, the rear axle, G, and the bolster H, and B is a central spring connecting the rear axle and bolster, but arranged upon a lower plane than the side springs. Each spring A is composed of leaves 1 2 3 4, as shown in Fig. 1. The springs are hinged to the bolster and axle in any suitable manner.

30 The spring B is braced by one or more braces, C, which, in Fig. 1, is arranged in a plane below the spring B, hinged at its front end near the central portion of the front axle, bent into a loop at the inner end, and connected to the 40 spring B above. The central spring, B, constituting the perch, and the spring-brace C are each of a single plate of steel, and are cross-braced by braces H² H², (shown in Figs. 1 and 2 as connected to the spring-brace and in 45 Figs. 3 and 4 as connected to the perch.)

The spring-brace may extend to the rear instead of the front, or two may be used below the perch, as in Fig. 3, or the perch may be placed in a lower plane and the spring brace 50 or braces arranged above, as shown in Fig. 4. In any event the brace or braces impart addi-

tional rigidity, and the three different points of connection upon three different horizontal planes aid in preventing the turnin_g of the axle or axles. An additional advantag_e of this 55 construction results from the king-bolt being braced so as to relieve the strain which occurs when the draft is at one end.

Heretofore, in this class of wagons, it has been common to use springs consisting each of 60 a single plate, as shown in Letters Patent No. 193,040, granted to me July 10, 1877, or each consisting of several plates constituting a leaf-spring. After extended experience with both these arrangements, I have found that with 65 the former the spring-platform is too rigid, and that when only leaf-springs are used, although greater flexibility was secured, there was such a lateral play of the leaves of such springs one upon the other, resulting from side 70 thrusts, that the side motion was permitted to a very deleterious extent. As a means of preventing such side play of the leaves, I applied box-loops over the ends inclosing the entire body of the spring, or formed the leaves 75 with lips s s, as shown in Fig. 5; but I found both alike defective, the loops retarding the free action of the leaves and the lips snapping off under the severe lateral strain.

By the above-described construction I prevent the side motion without in the least interfering with the freedom of action in each spring. This results from using a spring-perch, B, consisting of a single plate of steel, in connection with the leaf-springs, and bracing the 85 whole laterally together, the single plate-springs preventing the lateral movement to which leaf-springs are liable, while the latter insures the desired flexibility.

It will be apparent that the combined leaf-springs may be differently arranged and the number of springs varied as circumstances may require.

While the above-named features have been described as improvements on my triple-spring 95 wagon, as aforesaid, I wish it to be understood that they are applicable to various other wagons, and it is my purpose to employ them in such connections.

I claim—

1. The combination, with the leaf-springs of a spring-platform, of one or more single-plate

springs, combined and braced with the leaf-springs, substantially as set forth, to limit the side motion of the latter, as specified.

2. The combination of the springs A A and 5 central spring, B, arranged in a different plane, and cross-braces, one or more of said springs being made of a single plate and the others of superposed leaves, substantially as set forth.

3. The combination, with the spring-perch B, 10 of one or more spring-braces, consisting each

of a strip connected at one end near the center of the axle and bent at the inner end and connected to the spring B, substantially as set forth.

In testimony of my claims to said invention 15 I hereunto subscribe my name.

CYRUS W. SALADEE.
